UNITED STATES PATENT OFFICE.

THOMAS McG. AIKEN, OF PITTSBURGH, PENNSYLVANIA.

SAFE.

Application filed February 8, 1923. Serial No. 617,791.

To all whom it may concern:

Be it known that I, THOMAS McG. AIKEN, residing at Pittsburgh, in the county of Allegheny and State of Pennsylvania, a citizen of the United States, have invented or discovered certain new and useful Improvements in Safes, of which improvements the following is a specification.

My invention consists in improvements in the construction of safes. In Letters Patent of the United States No. 1,440,948, granted me January 2, 1923, I have described a safe made of symmetrical halves opening and closing on a medial plane. It is with such a safe that my present invention also has to do; specifically, my present invention is embodied in such a safe, so mounted and manipulated that its closed halves meet in a vertical plane and that its opened halves lie with their open sides exposed in horizontal plane. Such a safe I characterize a tub safe.

In the accompanying drawings Fig. I is a view in side elevation of the safe of my present invention when closed; Fig. II is a view of it in end elevation; Fig. III is a view in side elevation of the safe when open; Fig. IV is a view in plan from above of the safe halves when open; Figs. V and VI are fragmentary views in section, and to larger scale, illustrating the interengagement of the meeting edges of the safe halves and the locking mechanism; Fig. VII is a view corresponding to Fig. III, and illustrating a modification in detail.

The safe halves 1 and 2 are mounted on horizontal axes parallel to their open sides and parallel therefore to their plane of meeting. They are hinged together along their inner (when open) and lower (when closed) horizontal edges, as indicated at 3.

As shown in Figures I, II and III, the safe halves 1 and 2 are carried in a frame 4, being in this instance trunnioned in opposite pairs of arms 5 and 6 which swing pivotally in frame 4. It will be seen that the safe halves of these figures (I-III) as they open and close turn in curvilinear paths with respect to three centers of turning, (1) the pivot connecting the safe halves each to the other, (2) the axes on which the safe halves are individually trunnioned in the pairs of arms 5 and 6, and (3) the pivotal centers upon which the arms 5 and 6 swing in frame 4.

Opening and closing mechanism is added.

As best seen in Fig. II, the trunnions upon which the safe halves are hung in arms 5 and 6 are upon one side prolonged and carry, journalled for free turning, bearing blocks 7 and 8. These blocks 7 and 8 are cages for containing other parts, presently to be mentioned; but I here note that they are hollow, and that within the hollow spaces worm gears 12 and 13, integrally borne by the trunnions of the safe halves, may freely turn.

A block 21 carries (or, literally speaking, is carried by) a shaft 11 and a rod 14. The shaft and the rod extend in parallelism, one with the other, and the block carries both of these parts medially: they extend from the block to equal distances on either side. The shaft 11 is rotatable in block 21, and worm gear is provided, whereby shaft 11 may be rotated in its bearing in block 21, on rotation of a hand crank 15. Shaft 11 and rod 14 extend through blocks 7 and 8. The assembly is fully shown in the drawings. There is sliding movement of blocks 7 and 8 relative to shaft 11 and rod 14. It will be perceived that blocks 7 and 8, carried by the safe trunnions 6, themselves carry shaft 11 and rod 14 and with them block 21.

Within recesses in blocks 7 and 8 and feathered upon shaft 11 and meshing with worm gears 12 and 13 are worms 9 and 10. These worms being feathered to shaft 11 are capable of sliding along the shaft and are also rotatable in unison with the shaft; the worms further are confined within the blocks 7 and 8, which with respect to them become cages, by making thrust bearing at either end upon the body of the block.

The parts are positioned relatively as is shown in Figs. I and III, and it will be perceived that as the handle 15 is turned and the shaft 11 rotated, now in one direction, now in the other, the safe halves, hinged together as they are at 3, are brought from one to the other of the two positions illustrated. As the safe standing in closed position opens, the right-hand arms 6 swing in clockwise direction as there viewed, and the right-hand safe half 2 swings in clockwise direction and the pivot 3 rises. Shortly before reaching the position shown in Fig. III the arms 6, which had swung further, recede somewhat, in anti-clockwise direction, before the parts come to the ultimate position shown. The safe half on the left simu-

taneously swings oppositely. The trunnions upon which the safe halves 1 and 2 are hung may be so related with respect to the center of gravity of the halves as to facilitate swinging,—so related, for example, as to cause gravity to assist in holding the halves in closed position.

Figure V indicates the interengagement of the opposite faces of the rims of the safe 10 when closed. This interengagement is in zigzag line as is usual for fire-proof structure. The disposition of the particular planes is such as to admit of free swinging in complementary curved paths. The meeting surfaces may be faced with packing material of such nature as may be best suited to the particular service.

The means for locking the two halves together, when closed, are shown in Figure VI. This is a view in vertical section, showing the meeting edges of the upper wall of the safe when closed, and showing in elevation the locking members. These locking members consist of two bars 25 16 and 17, extending vertically along the side walls of the closed safe. One of them, the bar 17, may conveniently be anchored against any movement independent of the safe half 2 which carries it. The bar 16 is movable longitudinally in the safe half 1 which carries it. Means for shifting bar 16 longitudinally are found in a rotatable shaft 18 provided with a crank arm 19 engaging the member 16, and, externally of 30 the safe, a handle 20 for rotating the shaft 18. The opposite faces of the bars 16 and 17 are toothed, and the teeth are so disposed that when the member 16 is in one position the bars will come together, and 35 when, having come together, the bar 16 is shifted, the teeth will interlock, to prevent separation of the safe halves until the bar 16 is shifted oppositely again. Of course 40 both bars might be shifted if desired.

45 In Fig. VII I have shown a modification, in that the safe halves are mounted to rest by rollers 22, 23 upon the horizontal tracks 4^a, and so resting the safe halves manifestly are free to turn and spread laterally. The 50 trunnions, upon which the rollers are mounted, carry as before integrally the worm gears 12^a and 13^a, and they carry also, journaled to them the blocks 7^a and 8^a. The blocks 7^a and 8^a are held against turning by engagement of the rollers 24 with which they are equipped, with track 4^a. Shaft 11^a is turned directly by crank 15^a. With this explanation, the operation of the safe as shown in Fig. VII, in opening and closing will, from what has gone before, be clearly understood.

I claim as my invention:

1. A safe structure including a frame, duplicate complementary safe halves, pivoted together, and serving each as closure 65

for the other, and journaled on parallel horizontal axes in said frame, the said halves so mounted being adapted to be swung from position in which each half closes the other in vertical plane to the position in which both halves lie with their open sides disposed in a common horizontal plane.

2. A safe structure including a frame and 70 duplicate complementary safe halves, pivoted together, and serving each as closure for the other, and severally mounted for individual rotation and for relative recession and approach in said frame, together with means for turning the safe parts simultaneously and oppositely in such supporting frame.

3. A safe structure including duplicate complementary safe halves, pivoted together, and serving each as closure for the 80 other, and severally trunnioned in swinging arms, said arms in turn being pivoted in a suitable support, together with means for turning the safe parts simultaneously and oppositely upon said swinging arms.

4. A safe structure including duplicate complementary safe halves open each on one side and pivoted one to the other, means for sustaining said safe halves rotatably on horizontal axes parallel one to the other 90 and parallel each to the open side of the safe half, such means permitting of relative recession and approach of the safe halves, and means for imparting to the safe halves two simultaneous movements: 100 one, rotation of the safe halves each on its axis; the other, swinging of each safe half on the pivotal connection between the halves, whereby the safe halves may be moved simultaneously from one to the other of two alternate positions; one, wherein the safe halves, meeting open side to open side, constitute each a closure for the other; and the other, wherein the open sides of the two safe halves extend in a common horizontal plane.

5. In a safe structure the combination of a frame including opposite pairs of arms swinging pair by pair upon parallel axes, safe halves pivoted together and hung for rotation, each in one pair of said arms, and means for rotating said safe halves simultaneously and oppositely.

6. In a safe structure the combination of 115 duplicate complementary safe halves pivoted together and mounted for individual rotation and for relative recession and approach in a supporting frame, a pair of blocks axially mounted one upon each of said safe halves and with respect to which by virtue of such mounting said safe halves are rotatable, a rotatable shaft extending through the blocks and with respect to which said blocks are longitudinally movable, and means whereby shaft ro- 125 130

tation effects opposite turning of said safe halves with respect to said blocks.

7. In a safe structure the combination of 5
duplicate complementary safe halves, piv-
oted together, and having pivoted to them
a pair of blocks, a rotatable shaft extending
through said blocks and with respect to
which said blocks are longitudinally mov-
able, a pair of worms mounted on said
10 shaft rotatable in unison with said shaft
and movable longitudinally upon said
shaft, one of said worms engaged by each
of said blocks and movable in unison with
such block longitudinally of said shaft, a
15 worm gear borne by each safe half and
meshing each with one of said worms, and
means for rotating said shaft.

8. In a safe structure the combination of
duplicate complementary safe halves piv-
20 oted together and pivoted severally, each in
a pair of swinging arms, a rotatable shaft,

and means for causing said safe halves to
swing on said arm in response to shaft ro-
tation.

9. In a safe structure the combination of 25
two pairs of arms swinging in vertical
planes on parallel horizontal axes, two safe
halves trunnioned on horizontal axes, each
in one pair of said arms, and pivoted one
to the other, a block journaled upon the 30
axis of each safe half, a rotatable shaft ex-
tending through both bearing blocks and
means for turning the safe halves in their
mounting in the said arms in response to
35 shaft turning.

In testimony whereof I have hereunto set
my hand.

THOMAS McG. AIKEN.
